UNITED STATES PATENT OFFICE.

EDWARD E. GOLD, OF NEW YORK, N. Y.

STEAM-HEATING SYSTEM.

1,014,296.

Specification of Letters Patent.

Patented Jan. 9, 1912.

Application filed August 8, 1910. Serial No. 576,054.

To all whom it may concern:

Be it known that I, EDWARD E. GOLD, a citizen of the United States, residing in the borough of Manhattan, city, county, and 5 State of New York, have invented certain new and useful Improvements in Steam-Heating Systems, of which the following is a specification.

This invention aims to provide certain improvements in steam heating systems of the 10 type especially adapted for use in the heating of railway cars.

A feature of importance is the control of the system by a single handle or other controlling means, to determine the mode or principle under which the system shall operate.

Other features are referred to in detail hereinafter.

20 The accompanying drawings illustrate an embodiment of the invention.

Figure 1 is a perspective view of the principal parts of the heating system applied to one side of a railway car. Fig. 2 is a vertical sectional view through the discharge pipe and the non-automatic admission valve. Fig. 3 is a horizontal section on the line 25 3-3 of Fig. 2. Fig. 4 is a horizontal section through the automatic admission valve. Fig. 5 is a sectional view of the valve casting of Fig. 2 taken on a vertical plane at right angles to that of Fig. 2. Fig. 6 is a horizontal section on the line 6-6 of 30 Fig. 2.

35 Referring to the embodiment of the invention illustrated, the source of supply is a train-pipe A running under the car and provided with branches B to radiators at opposite sides of the car. From the branch B the 40 steam passes through an automatic admission valve C and thence by way of a riser D through the floor E of the car to a non-automatic admission valve within the car, and thence by a pipe F to the admission 45 pipe G of the radiator, the return pipe H of the radiator being provided with an expansion loop J through which the steam passes to the discharge pipe and thence down through the floor of the car.

50 In previous applications, for example, in my application No. 562,397, filed May 20, 1910, steam heating systems are described which can be operated at will either as pressure systems or as vapor systems. When operating under pressure the discharge is 55 closed sufficiently to prevent substantial loss

of steam; being opened intermittently by a trap to permit the escape of water of condensation, or being provided with a small drip passage sufficient to permit the escape 60 of water of condensation as fast as the latter forms, but not to permit the escape of any substantial quantity of steam. In the system illustrated, there are two discharge 65 passages, one by way of an outer pipe K through which the steam passes into the casting L of a thermostat, and thence by way of the trumpet M to the atmosphere, heating and expanding the thermostatic vessel N, which forces outward the stem O (Fig. 4) 70 of the automatic valve C so as to close the latter and prevent the further admission of steam. When, by reason of the lack of steam, the thermostat cools, the automatic admission valve C reopens and replenishes 75 the supply of steam, the passage being always free so that there is no pressure in the radiator but only what is called vapor, that is to say, steam under approximately atmospheric pressure. 80

Within the outer discharge pipe K is an inner discharge pipe P which communicates through a small opening at its upper end with the discharge pipe Q from the radiator loop J, so as to hold back the pressure while 85 permitting the escape of water of condensation. According as the discharge is open to the outer discharge pipe K or cut off therefrom, the system will therefore operate as a vapor system or as a pressure system. 90

A discharge valve is provided for determining whether or not the discharge shall take place through the outer pipe K, the drip opening into the pipe P being of importance only when the regular discharge 95 valve is closed, because of its negligible area as compared with the valve opening. The discharge valve R closes upon a seat S in the lower part of the casing T. The valve is provided with a central opening and a 100 depending tube U fitting within a ring V supported by arms within the casing T so as to leave a clear space outside of the ring for the passage of steam to the outer discharge pipe K. The inner discharge pipe P is fastened in the ring V. There is thus a telescoping joint between the pipes P and U. The valve R is pressed downward by a spiral spring W and is raised by means of a stem X having on its lower end a head with 105 a flange Y engaging the under edge of a ring Z which is screwed into an upwardly-project- 110

ing annular flange *a* integral with the top of the valve. The flange *a* is provided with perforations *b* and the head on the lower end of the stem *X* is provided with a radial notch or groove *c* in its under face so as to admit water to the opening *d* through the center of the valve when the stem is pressed down upon the top of the valve. A slight movement is permitted to the stem, 10 relatively to the valve, so that it can be moved both vertically and rotatively. By such movements it serves to keep the small opening clear of dirt, and this effect is increased by providing on the under side of 15 the head a tapered projection *e* fitting into a corresponding recess at the upper end of the opening *d*.

The casing *T* is a double valve casing carrying besides the discharge valve *R* a 20 non-automatic admission valve *f* adapted to close upon a seat *g*. The casing is provided with a diaphragm *h*, dividing it into two chambers. The lower chamber provides communication between the discharge pipe 25 *Q* of the radiator and the final discharge of the system; and the upper chamber provides communication between the source of supply and the pipe *F* which leads to the admission branch of the radiator. The admission valve *f* and discharge valve *R* are 30 mounted on the same spindle *X*, and the latter is provided with a packing ring *j* permitting it to move up and down in the diaphragm without substantial leakage. 35 The admission ports of the valve casing, *k* and *l*, Fig. 5, are in substantially the same transverse plane, the former discharging into the chamber at a point above the valve seat *g*, and the latter communicating with 40 the chamber at a point below such seat. The valve stem is provided with a screw thread *m* of high pitch screwing through a suitable part of the bonnet *n*, and is provided at its upper end with a handle *o* carrying a pointer *p* adapted to bear against 45 an approximately vertical face of a ring *q* upon the head of the valve casing. The pointer *p* is also a spring which by its bearing against suitable depressions in the face 50 of the ring *q* serves as an impositive lock to hold the valve in the position to which it is set, and tends also to throw it to the extreme position when the system is to be entirely cut off or is to be worked under pressure. 55 The ring *q* may be, for example, of the shape shown in Fig. 3 and with the words "Closed," "Vapor" and "Pressure" thereon so as to indicate by the position of the pointer *p* the condition of adjustment 60 of the system.

The operation of the system as a whole is as follows: With the pointer in the position of "pressure" the two valves are as in Fig. 2. Steam is admitted through the upper 65 chamber but is prevented from escape

through the lower chamber, only the drip orifice being open so that water may escape. The system accordingly operates under pressure. If the pointer *p* be turned approximately a third of a revolution it will 70 catch in the notch indicated in Fig. 3. The admission valve *f* will be moved halfway to its seat, leaving a sufficient clearance for a full flow of steam, and the discharge valve *R* will be lifted from its seat so that the 75 system will operate under vapor as previously described. By giving the valve stem a further turn forward about one-third of a revolution, the valve *f* is brought up 80 against its seat *g* and the steam is cut off entirely. The discharge valve is opened wide so as to insure the emptying of any water in the pipes as far as possible.

Various other known or suitable means 85 may be used for determining the principles under which the system is to operate; and instead of the true vapor and pressure systems herein described there may be substituted various known or suitable modifications thereof or departures therefrom 90

What I claim is:—

1. A steam-heating system having means including a discharge valve and an admission valve controlled by the temperature of the discharge, said means being adapted in 95 one position of said discharge valve to cause the admission of steam in unrestricted quantity and the maintenance of pressure in the system, and in another position to cause the admission of steam in restricted quantity 100 and the opening of the system to substantially atmospheric pressure, a non-automatic admission valve, and a single means for operating both said discharge valve and said non-automatic admission valve. 105

2. A steam-heating system having an automatic admission valve, a cut-off admission valve and a discharge valve, thermostatic means exposed to the discharge and controlling said automatic admission valve said 110 valve and thermostatic means being adapted to cause the system to operate as a pressure system with a free admission when said discharge valve is closed and steam is admitted, and to cause the system to operate as a vapor system with a restricted admission when the discharge valve is open and steam is admitted, and connecting means between said discharge valve and said cut-off admission valve by which said discharge valve may 115 be set in the open or the closed position when said cut-off admission valve is open. 120

3. A steam heating system having a cut-off admission valve and a discharge valve, means for permitting a restricted discharge 125 to cause the system to operate under pressure when said discharge valve is closed, thermostatically controlled means for controlling the supply of steam by the temperature of the discharge to cause the system to 130

operate under vapor when said discharge valve is open, and connecting means between said valves by which said discharge valve may be set in either open or closed position 5 when said admission valve is open.

4. A steam heating system having means including a discharge valve and an admission valve controlled by the temperature of the discharge, said means being adapted in 10 one position of said discharge valve to cause the system to operate as a pressure system with a free admission and a restricted discharge, and in another position to cause the system to operate as a vapor system with a 15 restricted admission and a free discharge, a non-automatic admission valve and a rotatable stem for operating both said discharge valve and said non-automatic admission valve, and having three different angular 20 positions corresponding respectively to cut-off, pressure and vapor.

5. A steam heating system having means including a discharge valve and an admission valve controlled by the temperature of the discharge, said means being adapted in 25 one position of said discharge valve to cause the system to operate as a pressure system with a free admission and a restricted discharge, and in another position to cause the system to operate as a vapor system with a 30 restricted admission and a free discharge, a non-automatic admission valve and a rotatable stem for operating both said discharge valve and said non-automatic admission 35 valve and having three different angular positions corresponding respectively to cut-off, pressure and vapor, and means for holding said stem impositively in each of said three positions.

40 6. A steam heating system having a valve casing, a radiator having inlet and outlet pipes communicating respectively at different points with said casing, said casing hav-

ing an admission port from the source of supply and a discharge port, the interior of 45 the casing being divided into two chambers, one communicating with the admission port and the inlet pipe and the other with the outlet pipe and the discharge port, a valve in the first chamber for closing or opening 50 the admission port, a valve in the second chamber for closing the discharge port, thermostatically controlled means for controlling the supply by the temperature of the discharge when both said valves are 55 open, and connecting means for operating the two valves simultaneously to close either one or to open both of said valves.

7. A steam heating system having a valve casing, a radiator having outlet and inlet 60 pipes communicating respectively at different points with said casing, said casing having an admission port from the source of supply and a discharge port, the interior of the casing being divided into two chambers, 65 one communicating with the admission port and the inlet pipe and the other with the outlet pipe and the discharge port, a valve in the first chamber for closing or opening the admission port, a valve in the second 70 chamber for closing the discharge port, thermostatically controlled means for controlling the supply by the temperature of the discharge when both said valves are open, 75 and a common stem on which both of said valves are mounted and by which they may be operated simultaneously to close either one or to open both said valves.

In witness whereof, I have hereunto signed my name in the presence of two subscribing witnesses.
